UNITED STATES PATENT OFFICE.

FREDERICK W. COY, OF BOSTON, MASSACHUSETTS, ASSIGNOR TO ARTHUR FULLER, OF SAME PLACE, AND E. C. JUDD, OF LYNN, MASSACHUSETTS.

SOLE-PRESSING MACHINE.

SPECIFICATION forming part of Letters Patent No. 393,215, dated November 20, 1888.

Application filed July 14, 1888. Serial No. 279,988. (No model.)

To all whom it may concern:

Be it known that I, FREDERICK W. COY, of Boston, in the county of Suffolk and State of Massachusetts, have invented certain new and useful Improvements in Sole-Pressing Machines, of which the following is a specification.

This invention has for its object to provide a simple and convenient machine whereby 10 boot and shoe soles may be molded or beaten out between male and female dies of appropriate form; and it consists in the several improvements which I will now proceed to describe and claim.

15 Of the accompanying drawings, forming a part of this specification, Figure 1 represents a side elevation of my improved machine. Fig. 2 represents a front elevation of the same. Fig. 3 represents a section on line $x-x$, Fig. 2. 20 Figs. 4 and 5 represent perspective views of parts of the machine in different positions. Figs. 6 and 7 represent, respectively, sections on lines $y-y$ and $z-z$, Fig. 1.

The same letters of reference indicate the 25 same parts in all the figures.

In the drawings, a represents the supporting frame or base, from which rise vertical guide-rods b . Fitted to move on said guide-rods are carriers c , which support the lasts or 30 formers d . I have here shown two lasts or formers d and supporting-carriers c ; but it will be remembered that in an organized machine there may be any desired number of lasts—as many in fact as can be conveniently 35 attended to by one or more operators—each last being operated independently by mechanism hereinafter described.

e represent the sole-forming dies, which are supported by a head, f , affixed to the upper ends of the uprights b , said dies being in 40 position to co-operate with the lasts or formers d . Each die e is adapted to rock or tip slightly, either lengthwise or crosswise, to enable it the better to conform to the bottom of 45 the last or former d , as usual in machines of this class.

The mechanism whereby each carrier and the last or former thereon are operated is as follows: Fitted to slide on the guide-rods b , under the carrier c , is a cross-head, g , which is

supported by links h , constituting a toggle-joint, the upper links h being pivoted to said cross-head, while the lower links h are pivoted at i to a standard or lug affixed to the base a . The meeting ends of said links are 55 connected by a rod, j , with a slide, k , which is adapted to move in fixed guides, and is provided with a trundle-roll, l , entering a cam-groove, n , in a wheel, o , affixed to a shaft, p . The rotation of said shaft, effected by means 60 presently described, reciprocates the slide and thereby causes the latter to alternately force the toggle-links h , h into and out of alignment, and thus raise and lower the cross-head g and with it the carrier c and its last or former d . 65 The carrier c is movable on the guide-rods independently of the cross-head, so that although it is raised by the upward movement of the cross-head it is capable of being more rapidly raised by preliminary lifting devices, hereinafter described, which act before the toggle-joints 70 to lift the last or former and bring the sole thereon into contact with the die, thereby holding the sole in position between the former and die before the molding pressure is imparted 75 by the action of the toggle-joints. The said preliminary lifting devices are, first, a sleeve, q , fitted to slide vertically on a guide-rod, r , Fig. 3, affixed to the cross-head g , said sleeve bearing at its upper end against an adjustable 80 screw, s , which works in a threaded socket in the carrier c ; secondly, a slide, t , fitted to move in vertical guides u , u on the cross-head g , said slide having a yielding rod, v , which bears against a flange, a' , on the sleeve q , and 85 is supported by a spring, w ; and, thirdly, a cam, b' , on the shaft p , arranged under the slide t , its perimeter supporting a roll, c' , on said slide.

The rotation of the cam b' when the roll c' rests in the depression of the cam, as shown in 90 Figs. 1, 2, and 4, causes the cam to raise the slide t , sleeve q , and former-carrier c , the former being thus rapidly raised until the concentric portion of the cam b' supports the roll c' , as shown in Figs. 3 and 5. The movement 95 thus imparted to the former brings the sole thereon into contact with the die e before the toggle-links h , h raise the cross-head, the cam b' being timed to operate, as described, before 100

the cam-groove *n* moves the slide *k* to straighten the toggle-links. After the former has been raised by the cam *b'*, it is supported by the concentric portion of the latter while the cross-head *g* is being raised by the toggle-links. The carrier *c* may be adjusted vertically by the screw *s*, the latter resting on the sleeve *q*, and raising the carrier when turned in one direction and lowering it when turned in the opposite direction. Provision is thus made for bringing the sole-supporting surface of the former into the proper relation with the die by the action of either the cam *b'* or the toggle-links, so that variations in the sizes of 15 formers and dies and in the thickness of soles may be compensated for. The rod *v*, which communicates the upward movement of the slide *t* to the sliding sleeve *q* and carrier *c*, is enabled by the spring *w* to yield when the former has come to a sufficiently firm bearing 20 on the sole between it and the die, thus preventing undue strain and friction on the cam *b'* in case the latter has not completed the upward movement of the slide *t*.

25 To enable the extent of upward movement imparted to the former *d* by the cross-head *g* to be adjusted, I provide the upper end of said cross-head with two inclines, *d' d'*, and form on the sleeve *q*, which slides in said socket, 30 two wings or lugs, *e' e'*, which may be turned so as to rest on said inclines at any desired points. The flange *a'* of the sleeve *q* is provided with a handle, *f'*, whereby the operator may turn the sleeve *q*, so as to cause its lugs *e'* to rest on the desired portions of the inclines *d'*. It will be seen that by turning the sleeve *q* so as to move its lugs toward the higher ends of the inclines the sleeve and the carrier and former supported thereby will be raised; 35 but when the sleeve is turned in the opposite direction it will be depressed with the carrier and former. The cross-head *g* is provided with vertical slots *h'* between the inclines *d' d'*, which slots are formed to receive the lugs *e'*, and thus permit the sleeve *q* to be depressed. 40 The inclines *d'* and rotary sleeve *q*, with its lugs *e'*, furnish a means whereby the operator may quickly adjust the former so as to accommodate its pressing-surface to the thickness of 45 the sole, said devices operating more quickly than the adjusting-screw *s*, which is designed only for such adjustments as are made necessary by changes in the sizes of forms and dies.

50 *i'* represents the driving-shaft which communicates motion to the shaft *p* through a worm, *j'*, on said driving-shaft and a worm-wheel, *k'*, on the shaft *p*. Said worm-wheel is loose on the shaft *p*, and is made operative by a sliding clutch, *l'*, which rotates with the shaft 55 *p* and engages with a clutch, *m'*, on the hub of the worm-wheel. The sliding clutch is normally held in contact with the clutch *m'* by springs *o'*, Fig. 3, and is separated from the clutch *m'* to make the worm *k'* inoperative by 60 a pin or stud, *p'*, which normally stands in position to act on inclines *q'* on the flange *r'* of the sliding clutch, and thereby move the clutch

back out of engagement with the worm-wheel. One of said inclines comes in contact with the pin *p'* when the former is fully raised by the toggle-links and the other incline acts on the pin when the former is depressed. The pin *p'* is normally held by a spring, *s'*, in position to act, as described, on the sliding clutch. A treadle, *t'*, and intermediate lever, *u'*, operated thereby are provided, whereby the operator may depress the pin *p'*, and thus release the sliding clutch and permit its springs to force it against the clutch *m'* of the worm-wheel. 80

The clutch above described and the means for operating it are old and well known; hence I have not deemed a minute description thereof necessary.

The operation is as follows: The cross-head 85 *g* and carrier *c* and former *d* being depressed and the cam *b'* in position to support the slide *t* in a depressed position, the operator, after placing a sole on the former, releases the clutch *l'* by depressing the treadle *t'* and pin *p'*. The 90 clutch at once engages the continuously-rotating clutch *m'* on the worm-wheel *k'*, and the shaft *p*, with its cams *n b'*, is rotated, the cam *b'* acting first and raising the slide *t* and former *d*, as already described, after which the cam *n* acts to force forward the slide *k* and throw the links *h h* into alignment, the molding pressure being thus imparted to the former. When the toggle-links are in line with each other, and the former *d* is in its highest position, the pin *p'*, acting on one of the inclines *q'* of the sliding clutch, withdraws the sliding clutch from the worm-wheel clutch, so that the former *d* remains in its pressing position as long as the operator desires. When the pressure 100 on the sole has continued long enough, the operator again depresses the treadle *t'*, whereupon the sliding clutch is again engaged with the worm-wheel clutch, and the shaft *p* is again rotated until the toggle-operating slide *k* is 105 drawn fully back and the cam-supported slide *t* is fully depressed, when the movement of the shaft *p* is again stopped, as before, by the automatic disconnection of the clutch *l'* from the clutch *m'*, the former *d* being thus kept depressed while the operator is removing the formed sole and applying another, after which 110 the shaft *p* may be again set in motion, as before.

The organized machine is provided with a 115 series of formers, *d*, and dies *e*, and an independent mechanism, such as is above described, to operate each former, there being a shaft, *p*, cam *b'*, and the described intermediate devices for each former.

The driving-shaft *i'* imparts motion to the worm-wheels of all the shafts *p* in the machine, said driving-shaft having a series of worms, *j'*, meshing with the worms *k'* of the shafts *p*, as shown in Fig. 6. Each shaft *p* is provided 120 with a sliding clutch, *l'*, as shown in Fig. 7, and each sliding clutch is normally held in contact with the clutch *m'* on the corresponding worm-wheel by springs *o'*, arranged as shown

in Fig. 3, and separated from said clutch by a pin or stud, p' , arranged and operating as hereinbefore described. A treadle, t , and intermediate lever, u' , operated thereby are provided for each pin or stud p' , so that the operator may depress either pin p' , and thereby release either sliding clutch and permit its springs to force it into engagement with the corresponding clutch of the worm-wheel. It is therefore within the power of the operator to put any shaft p in operation at will, and thereby operate each former independently, so that while one former is held in its highest position by the disconnection of its operating-shaft p from the driving-shaft i' , another former may be held in its lowest position to permit the application of a sole, and another may be moving toward or from its pressing position, so that the operator, after applying a sole to a former, d , and attending to its preliminary presentation to the corresponding die e by the cam b' , may leave it and attend to another former while the molding pressure is being applied and maintained. One operator can therefore attend conveniently to several formers.

The supporting-screw s of the carrier c has a hand-wheel, s'' , whereby it may be conveniently rotated.

It is obvious that the screw s may be omitted, in which case the carrier c might bear directly on the sleeve q .

If desired, the former may be supported directly by the cross-head g , said cross-head being in such case the former-carrier.

I claim—

1. In a sole laying or pressing machine, the combination of a driving-shaft, i' , a slide or cross-head, as g , a former-carrier adapted to slide with and also independently of the cross-head, mechanism, substantially as described, for giving the former-carrier an independent preliminary movement, said mechanism including a shaft, p , having a connection with the driving-shaft, as described, and a cam, b' , on the shaft p , automatic means whereby said shaft and cam are stopped after giving said movement to the former-carrier, and mechanism for positively moving the cross-head and thereby giving said carrier an additional movement under an increased pressure, as set forth.

2. In a sole laying or pressing machine, the combination of a driving-shaft, i' , a slide or cross-head, g , a former-carrier adapted to slide with and also independently of the cross-head, a shaft, p , having a connection with the driving-shaft, as described, a cam, b' , on said shaft p , adjustable connecting devices whereby motion is communicated from the cam b to the carrier, and whereby the normal height of the carrier may be adjusted, automatic disconnecting devices, substantially as described, whereby the shaft p and its cam are stopped after giving a preliminary movement to the carrier, and mechanism for positively moving

the cross-head and thereby giving the carrier an additional movement, as set forth.

3. In a sole laying or pressing machine, the combination of a driving-shaft, i' , a slide or cross-head, g , a former-carrier adapted to slide with and also independently of the cross-head, a shaft, p , having a connection with the driving-shaft, as described, a cam, b' , on said shaft p , and devices for transmitting motion from the cam b to the carrier, automatic means whereby the shaft p and its cam are stopped after giving the carrier a preliminary movement, toggle-links supporting the cross-head and carrier, a slide, t , movable independently of the cross-head and arranged to act on the carrier, a shaft having a cam, b' , arranged to support and operate said slide, and devices, substantially as described, operated by the rotation of said shaft, whereby the said toggle-links are alternately thrown into and out of alignment, as set forth.

4. In a sole laying or pressing machine, the combination of a slide or cross-head, a former movable with and independently of the cross-head, a power-driven shaft having the cams b' and n , a slide, t , supporting the carrier and supported by the cam b' , toggle-links supporting the cross-head, and a slide, k , reciprocated by the cam n and connected with the meeting ends of the toggle-links, as set forth.

5. In a sole laying or pressing machine, the combination of a shaft having the cams b' n , loose gear k , and sliding clutch l' , the driving-shaft, whereby the loose gear k is rotated, the cross-head g , the former-carrier c , movable with and independently of the cross-head, the slide t , whereby motion is communicated to the carrier from the cam b' , the toggle-links supporting the cross-head g , the slide k , engaged with the cam n , and the rod j , connecting the slide with the toggle-links, as set forth.

6. In a sole laying or pressing machine, the combination of the driving-shaft, the cross-head having the guide-rod r , the sleeve q , adapted to move on said guide-rod and having a flange, a' , the former-carrier c , supported by said sleeve, the shaft p , having a connection, as described, with the driving-shaft, the cam b' on shaft p , the devices connecting the cam b' with the flange a' , whereby the sleeve q and carrier c are given a preliminary upward movement independently of the cross-head, automatic mechanism, substantially as described, whereby the shaft p and its cam are stopped after said movement, and the toggle-links and operating mechanism therefor, whereby the carrier is raised to give the sleeve and carrier an additional upward movement, as set forth.

7. In a sole laying or pressing machine, the combination of the cross-head g , having the guide-rod r and inclines d' d' , the sleeve q , adapted to move vertically and rotate on the rod r , and provided with lugs e' e' , adapted to bear on said inclines, and the former-carrier supported by the sleeve q , as set forth.

8. In a sole laying or pressing machine, the combination of the cross-head having a guide-rod, the former-carrier, the interposed sleeve *q*, adapted to slide on the guide-rod as a support for the carrier, the slide *t*, having the yielding rod *v* bearing against a flange on the sleeve *q*, and the cam *b'*, whereby said slide and its rod are alternately raised and allowed to fall, as set forth.
9. In a sole laying or pressing machine, the combination of a die or former, as *e*, a last or former, as *d*, a carrier for the former *d*, a shaft, *p*, toggle-links supporting the former-carrier, the cam *n* and slide *k*, operated by the rotation of the shaft *p*, whereby the toggle-links are alternately thrown into and out of alignment to raise and lower the cross-head, a driving-shaft whereby the shaft *p* is driven, a loose gear on the shaft *p*, meshing with a gear or worm which is affixed to the driving-shaft, and an automatic clutch mechanism, whereby the shaft *p* is automatically disconnected from the driving-shaft when the former-carrier is at its highest and lowest points, as set forth.
10. In a sole laying or pressing machine, a series of sole pressing or molding mechanisms,

each including a former, *e*, a last or former, *d*, a carrier for said former *d*, a shaft, *p*, having a loose gear, *k'*, toggle-links supporting the former-carrier, and mechanism, substantially as described, operated by the rotation of the shaft *p*, whereby the toggle-links are alternately thrown into and out of alignment to raise and lower the cross-head, combined with a driving-shaft having a series of worms, *j'*, one for each of the gears *k'* on the series of shafts *p*, a series of automatic clutch mechanisms, whereby the shaft *p* of each pressing mechanism is independently disconnected from the driving-shaft when the former-carrier of said mechanism is at its highest and lowest points, and means, substantially as described, whereby each shaft *p* may be operatively connected with the driving shaft by the operator, as set forth.

In testimony whereof I have signed my name to this specification, in the presence of two subscribing witnesses, this 2d day of July, A. D. 1888.

FREDERICK W. COY.
